DESIGN FOR A MARBLE GAME APPARATUS

Carl R. Simpkins, Inglewood, Calif., assignor to
J. Frank Meyer, Flintridge, Calif.

Application June 23, 1934, Serial No. 52,307

Term of patent 3½ years

To all whom it may concern:

Be it known that I, CARL R. SIMPKINS, a citizen of the United States, residing at Inglewood, in the county of Los Angeles and State of California, have invented a new, original, and ornamental Design for a Marble Game Apparatus, of which the following is a specification, reference being had to the accompanying drawing, forming a part thereof:

I claim:

The ornamental design for a marble game apparatus, as shown.

Signed at Los Angeles, California, this 16th day of June, 1934.

CARL R. SIMPKINS.
